UNITED STATES PATENT OFFICE.

ISAAC N. DANN, OF NEW HAVEN, CONNECTICUT.

DESIGN FOR A FOOT-REST FOR CHILDREN'S CARRIAGES.

SPECIFICATION forming part of Design No. 30,191, dated February 14, 1899.

Application filed January 19, 1899. Serial No. 702,729. Term of patent 14 years.

To all whom it may concern:

Be it known that I, ISAAC N. DANN, of New Haven, in the county of New Haven and State of Connecticut, have invented and produced 5 a new Design for a Foot-Rest for Children's Carriages; and I do hereby declare the following, when taken in connection with the accompanying drawing and the letters of reference marked thereon, to be a full, clear, and 10 exact description of the same, and which said drawing constitutes part of this specification and represents a perspective view of a foot-rest for children's carriages embodying my design.

15 This invention relates to a design for the foot-rest of children's carriages; and it consists in the design, as hereinafter described, and shown in the accompanying illustration.

As herein shown, the foot-rest consists of a

drop A, the forward end B of which projects 20 outward, upward, inward, and outward, as a gooseneck. This projecting end is connected at both sides with the drop by compoundly curved arms C, and the spaces between the arms and the edge of the drop are partially 25 closed by scrolls D E, all as shown in the accompanying illustration.

I claim—

The design for a foot-rest for children's carriages, as herein shown and described. 30
In testimony whereof I have signed this specification in the presence of two subscribing witnesses.

ISAAC N. DANN.

Witnesses:

FRED. C. EARLE,
LILLIAN D. KELSEY.
